United States Patent Office

Des. 186,650
Patented Nov. 10, 1959

186,650

SCARF OR SIMILAR ARTICLE

Michael Angelo Susi, Brooklyn, N.Y., assignor to Original Plastics, Inc., Hoboken, N.J., a corporation of New Jersey

Application June 1, 1959, Serial No. 56,145

Term of patent 14 years

(Cl. D92—26)

The figure is a plan view of a scarf or similar article, showing my new design.

The rear view of the scarf is similar to the plan view shown.

I claim:

The ornamental design for a scarf or similar article, substantially as shown and described.
